CONNECTER FOR ELECTRICAL APPLIANCES

Filed Jan. 13, 1931

Henry J. Baum.

Inventor;

By John E. Kramer, Attorney

UNITED STATES PATENT OFFICE

HENRY J. BAUM, OF CLARION, IOWA

CONNECTER FOR ELECTRICAL APPLIANCES

Application filed January 13, 1931. Serial No. 508,542.

The subject-matter of the present invention relates generally to electrically heated appliances, and the improvements are directed to novel and unique means for making electrical connection with a heating element of said appliances.

Primarily, the object of the invention resides in the provision of means whereby an electric current may be conveyed to a heating element in a manner to permit of manipulating said appliance without twisting, or otherwise straining, the conductor cord.

Another object is to provide means whereby current supplying conductors may be readily attached, or detached from a heating element forming a part of an electrically heated appliance, such as a curling iron, or the like.

Still another object of the invention is to provide means in the form of contact members carried by the ends of a conductor cord and adapted to be maintained in spaced insulated relation with each other when assembled for connection to the insulated terminals of a heating element.

A still further object resides in the provision of means, including separable members, adapted to maintain said contact members in spaced and insulated relation to each other.

Another feature of the invention is to provide novel contact members embodying spring means for assuring a constant electrical connection between said members and the insulated terminals of a heating element.

Still another aim resides in the provision of a device of the above-mentioned character which comprises but a few simple parts, and which is sturdy in construction, efficient in operation, and capable of giving long and satisfactory service.

With these objects in view, together with others which will appear as the description proceeds, the invention resides in the novel formation, combination and arrangement of parts, all as will be described more fully hereinafter, illustrated in the drawing, and particularly pointed out in the claim.

In said drawing:

Figure 1 is an elevation, partly in section,

of an electric curling iron equipped with my invention.

Fig. 2 is an elevation of one end of a typical heating element about to be inserted within a pair of contact members forming the terminals of an electric conductor wire, one part of a split insulated casing being removed to expose said contact members.

Fig. 3 is an elevation of one of the insulated split members forming said casing.

Fig. 4 is an end elevation, slightly enlarged, of said casing wherein its split members are shown in assembled position and maintained therein.

Fig. 5 is a sectional view, slightly enlarged, and taken on the plane of the line 5—5 of Fig. 2.

Fig. 6 is a central sectional view of a slightly modified form of contact member.

Fig. 7 is a sectional view thereof and taken on the line 7—7 of Fig. 6.

Referring now more in detail to the accompanying drawing, wherein like characters of reference denote similar parts throughout the several views, let 5 indicate the handle portion of a curling iron, said handle being provided with an axial bore 6 for the reception of one end of the casing 7, the latter inclosing the usual heating element ordinarily comprising a coil of resistance wires, (not shown).

The other essential parts of an electric curling iron will be readily recognized by those skilled in this art, said parts comprising the jaw member 8, adapted to be operated in the usual manner by a thumb-pressed lever 9, pivotally supported by the member 10, as clearly shown in Fig. 1. The heating element, borne by the casing 7, comprises a coil of wire having its ends connected in the usual manner to terminals 11 and 12 separated by the insulation 13, as shown in Fig. 2. It will, of course, be understood that while the drawing shows an electric curling iron, such disclosure is illustrative rather than restrictive, as the device about to be described is adapted to be connected to many forms of electrically heated appliances which embody an incased heating element having insulated terminals, like unto 11 and 12, shown in Fig. 2. It will

further be observed upon inspection of Fig. 1 that said casing 7 and the terminals 11 and 12 are insertible within said bore 6 and adapted to be maintained in this position by means 5 of screw 14 passing through said handle 5.

Upon inspection of Fig. 2, it will be noted that the electric current conductor 15 includes wires 16 and 17 connected to the annular contact members 18 and 19 respectively, the ends 10 of said wires being preferably soldered to said members as indicated at 20 in Figs. 5 and 6. It is obvious that it is only necessary to maintain said contact members in spaced and insulated relation to assure an electrical 15 connection between said members and the terminals 11 and 12, when said terminals are inserted within said contact members and in the assembled relation shown in Fig. 1.

The means for maintaining the aforementioned spacing of said contact members comprises a casing, formed from insulated material, and including parts, or halves, 21 and 22, said parts, when united, defining a bore 23 and spaced recesses 24 and 25, said recesses being adapted to receive said contact members 18 and 19 respectively, as shown in Figs. 2 and 5. After said contact members have been affixed to said wires 16 and 17, the conductor 15 is placed in the bore 23a 20 of the part 21, said contact members being reposed in recesses 24 and 25, whereupon the other part 22 is applied and both of said parts maintained in the position shown by applying a sleeve 26 over the reduced portions 27 of said parts 21 and 22, as shown in Figs. 1 and 4. In view of this arrangement said contact members are arranged in spaced and insulated relation and when the terminals 11 and 12 engage said contact 30 members, the heating element of the appliance is electrically connected. Upon inspection of Fig. 1, it will be seen that the assembled casing is insertible within said bore 6 of the handle 5 and this position is maintained by a cap 28 suitably secured to said handle, as indicated at 29. Said cap 28 is provided with a central aperture 30 which engages the reduced portion 27a, of said casing, and thus the device is firmly mounted 40 in position, but subject to removal by operating the cap 28.

From the foregoing it is obvious that the connection between the contact members and the terminals of the heating element is such 50 that the former members may rotate over the terminals as the implement is used, thus preventing twisting of the conductor wires, so common in ordinary connections. When the terminals 11 and 12 are inserted within the 60 contact members, the insulation 13 is, of course, between said members, thus assuring the proper connection of the respective parts.

In Figs. 6 and 7 I have illustrated a slightly modified form of contact member, which 65 has been adopted to positively preclude the

likelihood of occasional shorts between the plain contact members and the terminals 11 and 12 when the implement is twisted during its manipulations. In this form, it will be noted that the marginal portion of the 70 contact member is recessed at 31 which opens into the bore 32, a leaf spring 33 being affixed within the recess and positioned in a manner to frictionally engage a terminal and assure a tight, yet removable, connection therewith. The bottom wall of the recess may be drilled, as indicated at 34, and the end of the spring wedged in place as shown. However, if desired, a small opening 75 may be drilled in one side of the contact member to terminate on the outside thereof, whereupon the spring may be inserted and the opening filled with solder from the lower side. In this way neither the 80 solder or the spring can loosen.

The two contact members 18 and 19 are firmly held in place when the two parts of the insulated casing are affixed together by means of the sleeve 26, yet the entire structure may be readily removed and disassembled by slipping said sleeve from the reduced portion 27. The device is practically 90 indestructible and long and satisfactory service is assured.

While the present is a disclosure of the 95 preferred embodiment of the invention, it is to be understood that the invention is not limited thereto, as various changes in the minor details of construction, proportion and arrangement of parts may be resorted 100 to without departing from the spirit of the invention as defined in the appended claim.

I claim:

In a device of the character described, the combination with a handle having an axial bore, and a connector mounted in said bore and having insulated terminals, a two-part insulated casing rotatably mounted in said axial bore and having a plurality of bores and spaced recesses and presenting a plurality of reduced portions, annular contact members mounted in said recesses and adapted to be electrically connected to said terminals, conducting wires seated in the smaller bore of said casing and connected 115 to said contact members, a sleeve embracing the larger reduced portion of said casing binding the parts of said casing together to maintain the contact members in spaced and insulated relation and clamping said conductor wires in the smaller bore of said casing, and an apertured cap fitting over the smaller reduced portion of said casing and being affixed to said handle to position said casing within the axial bore of said handle. 120

In testimony whereof I affix my signature.

HENRY J. BAUM.
